CLAIM

The ornamental design for a water bottle fountain with side bubbler, as shown and described.

DESCRIPTION

FIG. 1 is a perspective view of a water bottle fountain with side bubbler, showing our new, original and ornamental design;

FIG. 2 is a right side elevational view thereof;

FIG. 3 is a top plan view thereof;

FIG. 4 is a left side elevational view thereof;

FIG. 5 is a bottom plan view thereof;

FIG. 6 is a rear elevational view thereof; and,

FIG. 7 is a front elevational view thereof.

The broken line showing is included for the purpose of illustrating and forms no part of the claimed design.
